G. A. FISCALINI

OIL BURNER

Filed June 29, 1927

INVENTOR

GEORGE A. FISCALINI.

BY *Munro & Co.*

ATTORNEYS.

UNITED STATES PATENT OFFICE.

GEORGE A. FISCALINI, OF SAN LUIS OBISPO, CALIFORNIA.

OIL BURNER.

Application filed June 29, 1927. Serial No. 202,304.

My invention relates to improvements in oil burners, and it consists in the combinations, constructions and arrangements hereinafter described and claimed.

- 5 An object of my invention is to provide an oil burner in which the same air is utilized for placing the fuel under pressure and also for mixing with the fuel to form a combustible mixture.
- 10 A further object of my invention is to provide a device of the type described, in which the air and the fuel are mixed together at the tip of the burner, the pressure of the air and the fuel being dependent upon each other so
- 15 that a regulation of the flow of air will automatically regulate the flow of fuel, thereby forming a perfect mixture, whether a low flame is employed or a high flame.

Other objects and advantages will appear 20 in the following specification, and the novel features of my invention will be particularly pointed out in the appended claim.

25 My invention is illustrated in the accompanying drawing, forming a part of this application, in which—

Figure 1 is a vertical section through a storage tank showing the burner operatively connected thereto; and

30 Figure 2 is a longitudinal section through the burner, portions thereof being shown in elevation.

In carrying out my invention I provide a storage tank 1, which has a filler cap 2, an air compressor 3, and an automatic exhaust 35 valve 4. Oil is poured through the opening 5 and this oil is placed under pressure by means of the compressor 3.

An oil pipe 6 and an air pipe 7 lead from the bottom and top of the tank, respectively, 40 and are connected to a burner indicated generally at 8. Valves 9 and 10 control the flow of fuel and air into the burner 8. It will be noted from Figure 1 that a drain plug 11 is mounted in the pipe 6 for draining the contents from the tank 1, when the operator so desires.

In Figure 2 it will be noted that the fuel pipe 6 communicates with an inner pipe 12 of the burner 8 and that this pipe terminates 45 a short distance from the nozzle 13. A second pipe 14 encloses the pipe 12 and is in

communication with the air pipe 7. A nozzle 13 forms a mixing chamber 15 and from this chamber the mixture is forced through openings 16, and then through a small opening 17. These series of openings effectually break up the fuel into minute particles and thoroughly mix the particles with the air, so as to form a combustible mixture.

55 From the foregoing description of the various parts of the device, the operation thereof may readily be understood.

I have found from experience that a burner constructed along the lines set forth is adapted to burn fuel far more readily than can be 60 accomplished with other burners. This is due to the fact that the fuel is under the same pressure as the air and that these two elements unite at the top of the burner and then are forced through a pair of small openings 16, and then through a smaller single opening 17. The pressure behind the air and the fuel causes a thorough mixture of the two prior to their issuance from the mouth of the burner. I have diagrammatically shown the 65 burner as being disposed in an oven 18, or other device, to be heated.

70 The pressure is maintained by means of the compressor 3 and this pressure is strong enough to break up the fuel into minute particles, so that the burner can be ignited when cold. A change in the volume of the air by means of regulating the valve 10 will automatically adjust the amount of fuel flowing into the burner, so that the required amount 75 will be conveyed to the fuel to form a perfect combustible mixture. In this way the device is more or less automatic in operation.

80 Although I have shown and described one embodiment of my invention, it is to be understood that the same is susceptible of various changes and I reserve the right to employ such changes as may come within the scope 85 of the appended claim.

I claim:

90 An oil burner having an oil passageway therein and an air passageway surrounding the oil passageway, the walls of said air passageway extending beyond the end of the oil passageway for forming a mixing chamber 95 having a greater cross-sectional area than the cross-sectional area of the two combined

passageways, a partition closing the outer end of the chamber and having small openings therein for causing a slowing up of the oil and air in the chamber for partially mixing them and for mixing them still further as they pass through the openings, a nozzle for said burner spaced from said partition

and having a single opening therein, and means for applying the same pressure to the oil and to the air, and manually controlled means for regulating the flow of oil and air to said burner independently of each other. 10

GEORGE A. FISCALINI.
